EMBORESSED METAL FOIL

Edward Swallow, Bridgeville, Pa., assignor to Aluminum Company of America, Pittsburgh, Pa., a corporation of Pennsylvania

Continuation-in-part of design application Ser. No. 6,269, Mar. 17, 1967. This application Sept. 4, 1968, Ser. No. 13,391

Term of patent 14 years

Int. Cl. D5—03; D25—01

U.S. Cl. D54—2

FIG. 1.

FIG. 2.

FIG. 1 is a plan view of a sheet of embossed metal foil showing my new design.

FIG. 2 is a sectional view taken along line 2—2 of FIG. 1.

The sheet of foil being embossed, the design is raised on the one side of the sheet and is indented into the opposite side, the design on both sides being otherwise the same.

This is a continuation-in-part of my United States design application Ser. No. D6269 filed on Mar. 17, 1967 for an embossed metal foil and now abandoned.

I claim:

The ornamental design for an embossed metal foil, as shown and described.
